UNITED STATES PATENT OFFICE.

PETER MUNZINGER, OF PHILADELPHIA, PENNSYLVANIA, ASSIGNOR OF
TWO-THIRDS TO JAMES DALE WILSON AND WILLIAM HAYDON, BOTH
OF SAME PLACE.

GAS-PRESSURE REGULATOR.

SPECIFICATION forming part of Letters Patent No. 320,273, dated June 16, 1885.

Application filed February 24, 1885. (No model.)

To all whom it may concern:

Be it known that I, PETER MUNZINGER, a citizen of the United States, residing in the city and county of Philadelphia, in the State of Pennsylvania, have invented an Improvement 5 in Gas-Pressure Regulators, of which the following is a specification.

My invention relates to a class of devices for equalizing the flow of gas, notwithstanding varying pressures in the main and the variations produced by turning on or shutting off gas to or from burners in the building.

The object of my invention is the production of an apparatus adapted to supply gas at 15 a uniform pressure, and regulate with exactness in accordance with given demands its flow to one or more burners, whereby a steady and uniform pressure and supply to one or more burners is secured, notwithstanding the 20 continual variations of pressure under which the gas is delivered from the street-main to the regulator.

My invention relates specifically to that class of pressure-regulators in which the valve which 25 controls the inlet of the gas to the pipes leading to the burners is suspended from and connected with a float which is partially immersed in liquid glycerine or other suitable fluid, and in which both the float and the valve have, 30 under varying pressures, a movement in common, the valve automatically opening or closing to compensate for high or low pressures.

Apparatus embodying my invention is represented in the accompanying drawings, and 35 described in this specification, the particular subject-matter claimed as novel being herein-after definitely specified.

In the drawings, Figure 1 is a central vertical sectional elevation in the plane of the line 40 $z z$ of Fig. 4 of my entire device. Fig. 2 is an elevational fragmentary detail of the valve-box, a portion of which is shown as broken away to exhibit the perforated cylindric cap of the valve, from which the spherical bell or 45 movable part of the valve proper is shown removed. Fig. 3 is a central vertical sectional elevational view of the valve-box, the spherical bell of the valve and its connected hollow

spindle being shown in elevation. Fig. 4 is a top sectional plan through the tank and float, 50 section being supposed in the plane of the dotted line $x x$ of Fig. 1. Fig. 5 is a top sectional plan through the valve-box, valve-bell, and perforated valve-cap of the valve, section being supposed in the planes of the dotted line 55 $y y$ of Fig. 1. Fig. 6 is a top plan view of the valve-bell, the hollow valve-spindle which carries the bell of said valve being in section.

Similar letters of reference indicate corresponding parts. 60

In the drawings, Δ represents a closed and gas-tight tank or containing-vessel, preferably cylindriform, which is adapted to contain glycerine or other fluid, and in which the valve-float B is contained. This tank is erected 65 upon a suitable casting or valve-box, C , which contains the gas-regulating valve of the contrivance. The valve-box is conveniently a spherical shell, into which the gas-inlet pipe D , which leads from the meter, opens, and out 70 of which the gas-exit pipe E , which leads to the burners, passes.

The gas-inlet pipe terminates in a cap, F , provided with slots, perforations, or other openings, f . Externally this cap is preferably 75 cylindric, and is provided with two annular conical faces, $f^2 f^3$, which form valve-seats for the movable part of the valve, which is conveniently made as a sliding spherical bell, G , and which is conveniently provided with a 80 vertically-extending cylindriform throat or extension, g , adapted to travel against and in contact with guides f^4 , vertically erected from the top of the perforated cap F in such manner as to occasion the vertical movement of the 85 bell.

The bell is provided with an internal annular conical face, g^2 , and with an external annular conical face, g^3 , which, when the bell has dropped or descended to the full limit of 90 its downward movement, register, respectively, with the conical faces $f^2 f^3$ of the perforated cap, and by such registry make an absolutely tight joint, so that gas flowing through the inlet-pipe and out through the slots f in its cap 95 is contained within the bell and finds no exit

therefrom. When, however, the bell is raised to an extent sufficient to separate the respective annular conical faces, the gas finds vent not only below the bell through the then open 5 valve-seat formed between the conical faces f^3 g^3 , but also above the cap through the then open valve-seat formed by the conical faces f^2 g^2 through the throat of the bell, and is by such annular passages admitted to the interior 10 of the valve-box, whence it may pass to the gas-exit pipe. Of course, when the bell is but slightly lifted, a less amount of gas can pass to the exit-pipe than when the bell is to a greater or to its full extent lifted. The bell is, in a manner 15 described hereinafter, suspended from the valve-float B, which floats within the tank, and the normal set of the bell is such as to open the valve-seats to a predetermined extent and admit of a given and predetermined flow of gas 20 to the burners.

It is the object of this device, as well as of others of this particular class, to so regulate the movement of the valve by the pressure of the gas itself, that, when the demand at the 25 burners is varied, the pressure of gas within the pipes shall control and correspondingly vary the vertical position of the movable part of the valve, and the consequent vertical depth or extent of the annular openings or 30 inter-spaces between the conical faces of its valve-seats.

The connection of the bell or movable part of the valve proper with the valve-float is as follows: Across the top of the throat g of the 35 bell is a spider, g^x , or other suitable connecting device, to which is fixedly connected a vertically-extending hollow valve-spindle, H, which extends up through the top or crown b of the valve-float B, and is rigidly connected 40 therewith. This spindle is contained within and surrounded by a vertically-erected hollow sleeve, I, which springs from the bottom a of the tank, and at its upper extremity is provided with a circular guide, i, which closely 45 surrounds and supports against displacement the said valve-spindle. The valve-float is a miniature gas-holder open at the bottom and formed of a crown, b, and a depending cylindriform diaphragm, b'. 50 The float is equipped with an annular air-chamber, b², conveniently connected with the diaphragm, the cubic area of which is so calculated as to occasion the normal immersion of the float to a depth necessary to maintain 55 its connected valve sufficiently open to allow a supply of gas predetermined to the desired pressure upon a given number of burners.

The float or holder is provided with a central cylindriform diaphragm, b³, open at the 60 bottom, which incases the hollow sleeve I and prevents any possible leakage of gas through the circular guide i at the top of said sleeve into the interior of the float.

The tank is also provided with a vertically-extending air-tube, J, which passes through 65 its bottom and opens within the valve-float

very close to the crown thereof and above the possible level of the glycerine or other fluid within the float. This tube serves to admit atmospheric air within the float above the 70 level of the glycerine therein.

K indicates the glycerine or other fluid with which the tank is supplied, and in which the valve-float, through the instrumentality of its air-chamber, is suspended or floated. 75

The operation of the device is as follows: Assume that by the proportioning of the air-chamber the float and its connected valve have been set, so to speak, at a predetermined position—for instance, that represented in Fig. 1 of the drawings. Gas admitted through the inlet finds its escape through the then open valve-seats to and into the exit-pipe, and also through the hollow valve-spindle into the upper portion of the tank, so that it exerts 85 therein a normal pressure on the glycerine sufficient to depress its level within the tank slightly below its level within the float. The upper portion of the float is, of course, filled with air. Assume now that the gas is turned 90 on at any particular burner. Its escape through such burner occasions an instant relief of the pressure both within the valve-box and within the tank, the result of which relief is that the air within the float, not being counterbalanced by the previously-existing pressure of gas within the tank, assists to displace a certain amount of the glycerine from the float 95 and into the tank and permits the raising of the level of the glycerine within the tank, 100 whereby the float is slightly lifted, so as to lift the valve to a corresponding extent and admit a correspondingly increased flow of gas to the burner-pipe. If another burner is then lighted the same action is repeated and the valve is 105 still further opened. If, on the other hand, the gas is shut off at a burner, the gas, which up to the time of such shutting off had existed at a predetermined pressure, backs up, so to speak, or finds its vent through the hollow 110 valve-stem to the top of the tank, and, acting upon the crown of the float, occasions a depression of said float and a corresponding depression and closing of the valve, so that a 115 correspondingly less amount of gas is permitted to flow into the exit or burner pipe.

It is obvious that various mechanical modifications may be made. Thus, for instance, the form of the tank and of the valve-float may be modified, as may also be the means of supporting the hollow valve-spindle of the float. The precise mode of application of the valve to the hollow spindle may likewise be varied, and the mode of supporting the spherical bell for movement upon the perforated cap of the 125 valve may be also modified without departing from my invention.

Having thus described my invention, I claim and desire to secure by Letters Patent of the United States—

1. In a gas-pressure regulator, the following elements in combination: a tight tank for 130

glycerine or other fluid provided with an air-inlet, a valve box or casing provided with an inlet and an outlet for gas, a valve composed of a fixed and a movable portion contained 5 within said valve-box, a closed-top valve-float or air-holder suspended by means of an air-chamber in the fluid within the tank, and a hollow valve-spindle connecting together the said float and the movable portion of the 10 valve and adapted to convey the gas in the valve-box to above the valve-float and within the upper part of the tank, all arranged substantially as and for the purposes set forth.

2. The combination, in a gas-regulator, of 15 the tight or closed tank, the valve-float, the air-tube opening within said float, the bell or movable part of the valve having an opening or throat, and a hollow valve-spindle which opens above the crown of the float, is also open 20 at its lower end, and is so connected with the bell as to leave the throat thereof open for the passage of gas, substantially as and for the purposes set forth.

3. In a gas-regulator, the combination of 25 the valve-chamber provided with a gas inlet and outlet, the fixed perforated cap therein provided with conical faces, and the movable bell provided with corresponding conical faces and adapted to have a vertical movement with respect to the perforated cap.

4. In a gas-regulator, in combination with 30 the perforated cap provided with the guides f^4 , the bell surrounding and sliding thereon and provided with the vertical throat which 35 has a movement upon said guides.

5. The combination of the valve-chamber

provided with a gas inlet and outlet, the fixed perforated cap therein provided with conical faces, the movable incasing-bell provided with corresponding conical faces and adapted 40 to have a movement with respect to the perforated cap, the valve-float, and the hollow spindle connecting the bell with the float and passing through the crown of the float.

6. The combination, in a gas regulator, of 45 the tight or inclosed tank, the valve-float provided with the central cylindric diaphragm, the air-chamber, and the hollow valve-spindle open at both ends and opening 50 above its crown, and the air-tube opening within said float, substantially as and for the purposes set forth.

7. The combination of the tank containing glycerine or kindred fluid and provided with the air-tube, the valve-float provided with 55 the air-chamber and floating therein, the valve-box provided with a gas inlet and outlet, the perforated cap or fixed portion of the valve, the incasing-bell or movable portion of the valve, and the hollow valve-spindle 60 connecting together the bell and the valve-float and opening on the one hand within the valve-chamber and on the other hand above the float and within the tank.

In testimony whereof I have hereunto signed 65 my name this 13th day of February, A. D. 1885.

PETER MUNZINGER.
